pany of California, Los Angeles, Calif., a cor-
poration of California

Application September 19, 1933, Serial No. 690,094

6 Claims. (Cl. 204—24)

This invention relates to the separation of wax from wax-bearing oil. The invention relates more particularly to the electrical separation of suspensions of precipitated wax from oil.

5 When the temperature of lubricating oil containing wax or paraffin is sufficiently lowered wax or paraffin is found to begin to be precipitated from solution in the form of a colloidal suspension and as the temperature is further lowered, more 10 wax is precipitated until the oil and wax mixture finally congeals to a semi-plastic or even solid mass. Oils containing a large quantity of wax will have relatively high congealing temperatures and oils containing a small quantity of wax will 15 correspondingly have low congealing temperatures. Thus it is apparent that the presence of wax limits the minimum temperature at which lubricating oils containing it can be used, by congealing or solidifying at low temperatures. The 20 pour point of a lubricating oil is that temperature 5° F. above the temperature at which the oil, under certain specified test conditions, congeals or ceases to flow and it is apparent that the presence of wax or paraffin in lubricating oil greatly influences 25 this characteristic of the oil. Therefore, in the production of lubricating oil it is necessary to remove a large proportion of the wax or paraffin present therein in order to lower its pour point and thereby extend the lower range of temperatures 30 at which it retains its lubricating qualities.

Wax has been separated from oil by a number of processes, three of which are the "cold settling process", "cold pressing process" and the recently 35 developed "electrical process". In the separation of wax from wax-bearing oils by the electrical process the wax-bearing oils are mixed with suitable diluents, the solution of oil and diluent chilled to a temperature at which the wax precipitates 40 from solution and the resulting mixture of wax-bearing oil, diluent and the suspension of precipitated wax subjected to an electric field between electrodes submerged in said solution. A major portion of the chilled precipitated wax suspension under the influence of the electric field 45 is separated from the oil-diluent solution in the form of a deposit upon the electrodes between which the said treating field is maintained. The oil-diluent solution thus freed from wax is then 50 distilled to recover the diluent and the wax free oil.

After a short period of electrical treating to remove precipitated wax from the chilled wax-bearing oil according to the hereinbefore described process the electrodes upon which the

wax is deposited become thickly coated with the deposited wax and it is necessary that this wax be continuously removed in order to maintain the apparatus in operative condition. If the wax is allowed to accumulate to an appreciable thickness 5 on the electrodes it decreases the effectiveness of the electrical precipitating and depositing action and reduces the cross sectional area of the passage between the electrodes through which the oil undergoing treatment flows. This reduction in 10 cross sectional area of treating space results in an increase in velocity in the wax-bearing oil undergoing treatment and a consequent decrease in time during which the oil remains in the treating field and thus the capacity of the treater is 15 either reduced or the thoroughness of the treating impaired by allowing an accumulation of wax on the electrodes. Furthermore, the wax may in time accumulate to the extent that the entire 20 treating space between the electrodes is filled with it and the wax-bearing oil either forced to channel its way through the wax or be entirely stopped from flowing. The means heretofore employed for removing deposited wax from the electrodes have been in the form of scrapers which returned 25 the wax accumulations to the oil-diluent solution from which they were formerly deposited. Subsequent settling of the thus removed wax in the treated oil was thereby made necessary to accomplish final separation. 30

Apparatus for the electrical deposition of wax from oil may be constructed to operate over long periods of time without attention by providing said apparatus with a large area of electrode surface and suitable mechanical means for maintaining this surface reasonably free from deposited wax. Moreover the wax may be positively removed from the electrode surface out of contact with the wax-bearing oil and directly disposed of without recontacting or being returned 40 to the oil. 35

Objects of this invention, therefore, are to provide an apparatus for dewaxing oil which will be efficient, of high capacity and capable of operating for long periods of time without attention. 45 Other objects are to provide an electric treater for dewaxing oil in which the completeness of the separation of precipitated wax from the wax-bearing oil will be a maximum; in which the electric treating zone will be continuously maintained 50 in operative condition by mechanical removal therefrom of accumulated wax, and in which the said mechanical removal of accumulated wax is positively accomplished out of contact with the 55 wax-bearing oil and positively removed from the

treater without recontacting the said wax-bearing oil or the dewaxed oil.

In general these objects are attained according to the invention by providing an electric treater structure incorporating a large movable electrode surface area adapted to be removed from the wax-bearing oil after a wax deposit has been formed thereon and suitable mechanical scraper means for periodically or continuously freeing said electrode surfaces from said accumulated deposited wax while removed from and out of contact with either the said wax-bearing or dewaxed oil. These objects are also attained according to the invention by providing suitable mechanical means for positively removing the wax from the electric treater without recontacting either the wax-bearing oil or the dewaxed oil from which said wax was deposited.

The invention broadly stated includes a process and apparatus for removing wax from wax-bearing oil wherein a movable electrode is placed in contact with the wax-bearing oil and wherein said electrode receives a layer of electrically deposited wax on its surface while in contact with said oil and wherein after said deposition of wax, the surface of said movable electrode carrying the layer of deposited wax is removed from contact with the wax-bearing oil and the said deposited wax layer mechanically removed therefrom while out of contact with said wax-bearing oil.

The invention more specifically resides in a process and an apparatus adapted to carry on the process wherein a continuously moving electrode surface is maintained in partial contact with oil to be dewaxed, and wherein a mechanical scraper is provided for removing deposited wax from the moving surface of said movable electrode, said removal of deposited wax being accomplished by said scraper while out of contact with the oil and wherein provision is made to positively eject said wax from the treater without recontacting said oil and without necessitating subsequent settling for separation and wherein means is provided to wash adhering oil from the deposited wax surface prior to its removal by the scraping means and wherein oil circulation means is provided to accomplish a continuous circulation of substantially dewaxed oil through the treater and through the electrical field therein and wherein provision is made for constantly withdrawing a portion of the dewaxed oil from the said circulating body of oil and wherein provision is made for constantly adding an equal quantity of wax-bearing oil to said circulating body of oil, and wherein local refrigeration of the wax-bearing oil at the surface of the electrode is provided for and wherein suitable means is provided for imposing a high electrical potential upon the said oil at the said electrode.

Other objects, advantages and features of the invention will be evident hereinafter.

The accompanying drawing illustrates one embodiment of the invention in which Figure 1 is a sectional elevation through the axis of the treater, Figure 2 is a cross section through the treater taken at line 2-2 in Figure 1, Figure 3 is a section through wax collecting trough on line 3-3 and Figure 4 is a similar section through the wax collecting trough illustrating an optional arrangement of means for disposal of wax.

The treater unit illustrated in Figures 1 and 2 is provided with a rectangular enclosure or tank 10, inside of which a hollow, cylindrical drum electrode 11 is centrally, coaxially and rotatably

supported on bearings 13 and 14. Slow rotation of said drum 11 is accomplished by means of an electric motor 16 driving said drum through shaft 17 which extends into tank 10 through stuffing box 18 and on the end of which is located a worm pinion 20 which meshes with worm gear 21 which is in turn solidly fastened to drum 11 through drum shaft 22.

A segmental cylindrical electrode 25 is coaxially positioned below said drum electrode 11, by insulating support 27 with a short free space therebetween as shown at 28.

The insulator 27 in addition to being a support for electrode 25 is hollow and forms an inlet between the outside of the treater unit enclosure 10 and the space 26 between the electrodes. A pump 30 driven by an electric motor 31 is provided for circulating oil from the space surrounding the electrode 25 in the enclosure 10 to and through said space 26 between the said electrodes. Oil from said space in the container 10 outside of electrode 25 is withdrawn through two outlets 32 and 33 through valves 34 and 35 and suction lines 36 and 37 to pump 30 from which it is discharged through valve 38 and inlet connection 41 through the insulator 27 to the space 26 between the electrodes and flows therebetween in a substantially axial direction with respect to drum 11 to return to the before mentioned space in container 10. A T 39 is provided between the discharge of the pump 30 and the valve 38 to which a line 42 is connected and through which a portion of the circulating oil may be continuously withdrawn. A T 44 is provided between valve 38 and inlet connection 41 to which a line 35 45 is connected and through which a quantity of the wax-bearing oil may be continuously introduced to the circulating system. A valve 46 in the oil inlet line 45 limits the quantity of oil introduced into the system and it is regulated 40 by a liquid level float control 48 in order to maintain a liquid level in the treater inside of container 10 approximately as shown by liquid level line 50.

A scraper 52 and trough 53 extend along and 48 make contact with the full length of drum electrode 11. A heater element 54 shown in Figure 3 is located near the bottom of the trough 53 and extends throughout its length. Electrical connection is made to the element through conductor 55 and insulator 56 and the circuit completed through the ground. A bracket 57 supports the grounded end of the heater element under tension in its proper position near the trough bottom. The purpose of this heater element is to heat and melt the wax shavings in the bottom of trough 53 after they are removed from the drum electrode by scraper 52. An outlet pipe 58 with valve 59 makes connection with the end of the trough 53 through the wall 10 60 of the treater unit container and serves to drain melted wax from said trough and from said treater. A wax screw mechanism may in some cases be employed in the trough to eject the solid wax from the treater as shown in Figure 4. Here 65 a screw 60 is employed to move the wax along the trough bottom to a depression 61 where it is allowed to accumulate in sufficient quantity to be withdrawn by means of a wax pump 62.

A spray connection 65 carrying spray head 66 70 which extends along the length of the drum 11 enters the treater unit at 67 above the upward moving side of said drum 11.

A vapor outlet pipe 70 in the top of the treater unit container 10 serves, through valve 71, to 75

exhaust gases and regulate pressures and temperatures in container 10.

5 A high tension lead-in insulator 73 is provided in the top of the treater unit through which electrical connection is made between a high voltage generator 74 and the electrode 25 by way of conductors 75 and 76. The electrical return circuit to the generator 74 is completed by way of the drum electrode 11, the ground and ground connection 77.

10 A pipe 80 extends into the hollow drum electrode 11 through the hollow drum shaft 22 and through flange 81. Flange 81 closes the end of a side outlet connection 82 which is placed coaxial 15 with the drum 11 on the end of the treater unit container 10 and into which shaft 22 projects through a stuffing box 83. The hollow shaft 22 is open ended and connects the inside of the drum 11 with the space 84 inside of the side outlet connection 82. A vapor outlet pipe 85 connects with said side outlet connection and serves to vent drum 11 of gases by way of hollow shaft 22 and space 84. Spacer rings 87 and 88 attached to the inside of the container opposite the ends 20 of the drum electrode 11 serve to shield the said ends thereof from contact with waxy oil and thus prevent wax accumulation where no provision is made for its removal. Slight clearance is allowed between the rings and drum. A liquid refrigerant, 25 such as a normally gaseous hydrocarbon may be introduced into drum 11 through pipe 80 which extends therethrough. The normal liquid level of the thus introduced refrigerant is maintained approximately as shown by liquid level line 86.

30 The operation is as follows: A body of substantially wax free oil or an oil having a pour point which is practically that which is desired in the finished product is established in the treater unit within the container or tank 10, filling approximately the lower half thereof and the 35 space between the drum electrode 11 and the segmental cylindrical drum 25 to a liquid level as shown at line 50. Circulation of this oil is established and maintained between the said electrodes 40 11 and 25 by means of a pump 30 driven by a motor 31. Pump 30 takes suction from the body of oil in the treater through outlet connections 32 and 33 on either side of the insulating support 27 through valves 34 and 35 and lines 36 and 37

45 and discharges the thus withdrawn oil through valve 39 and inlet connection 41 and through hollow insulating support 27 into the said space between the electrodes 11 and 25. The oil thus forced into the space between electrodes 11 and 50 25 flows in a longitudinal and substantially horizontal path therebetween to the ends of the said electrodes where it returns to the body of oil from which it was withdrawn, thus completing the cycle of circulation. A portion of this circulated oil is withdrawn continuously through the 55 withdrawal line 42 as the finished product while an equal quantity of wax-bearing oil is continuously introduced into this circulating stream through valve 46 and line 45. A float control 48 60 regulates the rate of introduction of wax-bearing oil into the system by tending to close valve 46 when the liquid level rises and tending to open valve 46 when the liquid level lowers in container 10.

65 70 Refrigeration of the circulated oil is normally accomplished by chilling the hollow drum electrode from the inside and this refrigeration is accomplished preferably by introducing a normally gaseous hydrocarbon, such as propane through line 80 into the inside of the drum 11 to

establish a liquid level therein approximately as shown at 86. Evaporation of this liquid inside of drum 11 provides the necessary refrigeration and the resulting vapors are allowed to escape therefrom through the hollow shaft 22, side outlet 5 connection 84 and the vapor vent pipe 85. Heat exchange with the oil undergoing treatment takes place through the walls of the drum 11 between the refrigerant inside thereof and the film of oil contacting the outside surface of said drum. 10 The thus cooled film of oil which extends over the contacted area of the drum throughout the space between said drum electrode 11 and said segmental cylindrical electrode 25 is cooled sufficiently to precipitate wax from solution. The 15 wax thus precipitated from solution lies in a region very close to the surface of the outside under surface of the drum 11, and under the influence of the electrical potential established through the oil between electrode 25 and the surface of drum electrode 11 readily attaches itself to said submerged surface of said drum 11. Just enough wax-bearing oil is introduced into the circulating oil passing between the electrodes to form this wax precipitate at the temperature 20 maintained at the surface of the drum 11 while the bulk of the circulated oil in the treater outside of the space between the electrodes is sufficiently wax free to be substantially free from wax precipitate at the slightly higher temperature 25 maintained therein. In other words, the wax concentration is so adjusted that at the electrode surface temperature only local precipitation of wax occurs in the treating zone between the electrodes and this only in a film of limited 30 thickness close to the surface of said refrigerated electrode surface 11.

35 The drum electrode 11 is slowly rotated at approximately two R. P. M. by means of electric motor 16 through worm pinion 20 and worm gear 21, as explained hereinbefore, said rotation being at a suitable speed to allow the accumulation of deposited wax on the surface of the drum 11 while in contact with the liquid. As the drum rotates, as shown, in a counterclockwise direction, the surface of the wax coating which was previously in contact with the oil is constantly withdrawn from the liquid into the gas space thereabove. As the rotation of the drum continues that wax film which was deposited in contact with the liquid is removed from the surface of the electrode 11 by means of scraper 57 which makes contact along the length thereof and the thus removed wax moves down the inclined surface of the said scraper to the bottom of the 45 trough 53 where it comes in contact with a heating element 54. Sufficient heat is imparted through element 54 to the wax shavings in trough 50 53 to melt them and the resultant liquid wax is withdrawn from the end of the trough through 55 an outlet pipe 58 and a valve 59.

60 The deposited layer of wax adhering to the drum surface as it is withdrawn from the oil by rotation, may be washed by a spray of a suitable solvent to remove adhering oil and this is provided for through a spray head 66, the supply for which enters the treater through pipe 65 and inlet connection 67.

65 70 During operation a unidirectional high electric potential gradient in the region of 45,000 to 60,000 volts per inch is maintained between the electrodes and this high potential is supplied from a high tension generator or other suitable source through conductor 75, lead-insulator bushing 73 and conductor 76 to the electrode 25. 75

The return circuit is completed from drum 11 through the ground and ground connection 17 to the said generator.

When it is desired to dissolve the wax-bearing oil in a suitable diluent before treating to maintain the desired fluidity at low temperatures this dilution may be effected before introduction of the resulting solution into the treater through line 49. Under some conditions of operation it is 10 desirable to employ a normally gaseous hydrocarbon diluent, such as propane, in solution with the oil in the treater, to accomplish either partial or complete refrigeration. As described hereinabove, this diluent may be added to the 15 flowing stream of wax-bearing oil under pressure and evaporation of the thus added diluent allowed to take place inside of the treater at reduced pressure. The pressure inside of the treater and thus the temperature of the contents 20 of the treater is regulated by the vapor outlet valve 71.

In normal operation the bulk of the oil in the treater is maintained at a temperature only slightly above the cloud point and, as described 25 hereinabove, wax precipitation caused to take place only within the film of oil contacting and lying close to the refrigerated drum electrode surface. This precipitation is caused by the localized chilling of the said film of oil, through heat 30 exchange with the cold electrode surface, to a temperature below its cloud point. Regulation of the temperature of the surface of the drum electrode to the proper degree may be accomplished by varying the pressure upon the liquid 35 refrigerant therein in a manner similar to that described for the refrigeration of the bulk of the oil in the treater. The temperature of the contents of the drum electrode may vary from -20 to -40° F.

Instead of employing normally gaseous diluents in the wax-bearing oil for refrigeration, it is sometimes desirable to cool the oil, either prior to introduction into the treater or during recirculation thereof, by indirect heat exchange with 40 a refrigerant. Cooling of the oil either by external indirect heat exchange means or by indirect heat exchange through the refrigerated drum electrode, is desirable where the oils undergoing treatment are sufficiently fluid at the low temperatures to be treated without diluents or where 45 heavy diluents, such as dewaxed lubricating oil, kerosene, gas oil and the like are employed. The reduced solubility of wax in heavy diluents as compared to light diluents makes the employment 50 of heavy diluents desirable in the herein described process and apparatus. It is especially desirable to employ a portion of the previously 55 dewaxed oil product as a diluent since subsequent separation of oil and diluent is then unnecessary. Recirculation of treated oil as described hereinbefore provides a method of operation in which the circulated dewaxed oil serves as the diluent 60 for the added wax-bearing oil.

It has been found that the wax particles in 65 most suspensions of precipitated wax resulting from chilling of wax-bearing oil are negatively charged. Therefore, by providing for a positive polarity on the movable drum electrode surface, the deposition of a major portion of the wax 70 on the said surface is insured and it is unnecessary to provide means for cleaning the negative

stationary electrode. Where the charges on the precipitated wax particles are found to differ from this the polarities of the electrodes may, obviously, be reversed as required to cause the deposition to take place on the electrode which is provided with means for wax removal.

It has been observed that a cold surface in contact with a wax-bearing oil tends to collect a film of precipitated wax. It is, therefore, an advantage to combine this function with that of the electric field by cooling the electrode on which the precipitated wax is electrically deposited. It is also an advantage to cause the wax, by localized chilling, to be precipitated in a region which is very close to the surface upon which it is 15 electrically deposited.

The apparatus is not to be limited to the treatment of oils for the removal of wax but is applicable to the treatment of similar substances or for the removal of asphalt, asphaltines, petroleum, sludges and other substances and impurities both solid and plastic.

The foregoing is merely illustrative of one apparatus and the invention is not limited thereby but may include any apparatus which accomplishes the same within the scope of the invention.

We claim:

1. A process for the separation of wax from wax-bearing oil which comprises circulating a body of substantially wax-free oil in a continuous 30 path between electrodes charged to a high electric potential difference, introducing a wax-bearing oil to be dewaxed into said first mentioned oil, depositing wax on one of said electrodes and removing oil from which wax has been removed 35 from said path.

2. A process for the separation of wax from wax-bearing oil which comprises commingling said wax-bearing oil with substantially wax-free oil, contacting said mixture with a cold surface 40 and precipitating wax from the mixture, passing said mixture in a continuous path between electrodes charged to a high electric potential difference to deposit wax on one of said electrodes, removing wax deposited upon said electrode and 45 withdrawing wax-free oil from said path.

3. A process for removing wax from wax-bearing oil comprising circulating a body of relatively wax-free oil in a continuous path between electrodes charged to a high electric potential difference, adding wax-bearing oil to said path, maintaining a portion of said circulating body of oil at a temperature at which wax is precipitated 50 from said added wax-bearing oil, removing wax from said path and removing relatively wax-free oil from said path.

4. Apparatus for dewaxing oil comprising a pair of electrodes, means to maintain one of said electrodes at a low dewaxing temperature, means to impress an electric potential between said electrodes, a reservoir for containing a quantity of oil and means to circulate oil from said reservoir through the space between said electrodes and return to said reservoir.

5. An apparatus according to claim 4 and means for adding a wax-bearing oil to oil circulated from said reservoir.

6. An apparatus according to claim 4 in which one of said electrodes is a rotatable drum.
